UNITED STATES PATENT OFFICE.

ALFRED E. GARDNER, OF WICHITA, KANSAS.

COLLAR CLASP.

Application filed June 4, 1921. Serial No. 474,952.

To all whom it may concern:

Be it known that I, ALFRED E. GARDNER, a citizen of the United States, residing at Wichita, Kansas, have invented certain new and useful Improvements in a Collar Clasp, of which the following is a specification, reference being had therein to the accompanying drawing.

This invention comprises a collar clasp. It is contemplated to produce a device of this character which may be made in resilient wire or the like, cheaply, the component portions carrying pin points for insertion in portions of a collar and having a pulling action which tends to keep the collar flap from bending or crumpling, wherein a hook is provided on one component and an eye on the other, insuring the maintaining of the collar flaps in close relationship when the device is applied; wherein the entire device is placed so as to be invisible when used in connection with a necktie, being so placed as to be hidden by the tie and held in place by it; and wherein a portion of each component is constructed to maintain the hook and eye portions in bent back relationship to the front of the collar so as to provide resting space for the tie.

Other objects and advantages will in part be apparent and in part be brought out in the specification.

A drawing is annexed, illustrating an embodiment of the invention, the following views being shown:

Fig. 1, is a view in front elevation showing the invention applied to a collar, the tie being removed;

Fig. 2, is a rear elevation of the same, portions of the collar being broken away;

Fig. 3, is a view in top plan showing the device detached from the collar;

Fig. 4, is a view in transverse section on line 4—4 of Fig. 1.

In these views 1 and 2 designate component members constituting the collar clasp. Each component comprises a central portion 3, in one instance formed to constitute an eye, and upon the other formed to constitute a hook. From this central por-

tion there extend spaced apart arms 4, normally extending outwardly from the central portions and diverging toward their outward extremities, but approximately in parallelism when inserted as shown in Figs. 1 and 2. For the purpose of insertion other arms 5 are extended in angular relationship to arms 4, and provided at their extremities with pointed or pin portions for insertion in the inner lining of a collar flap. By having arms 4 made of resilient material and diverging, they may be pressed together when inserting the pin points and thus create a stretching or pulling action at the extremities of arms 5, which tends to keep the collar flap from wrinkling.

Means are provided for holding back the hook and eye portions of the components so as to provide a space for a tie, as best seen in Fig. 4. To this end each arm 5, is provided, intermediate its ends, with a looped portion 6, set at an angle to the plane of the arms 4, so that when in engagement with and bearing against a portion of the collar flap, these looped portions will hold the arms 4 back in angular relation to the plane of the front of the collar to provide a space for the tie.

While the invention is illustrated in the embodiment here shown, minor changes are contemplated within the scope thereof as set forth in the claims.

What I claim is:

1. A collar clasp comprising a hook component; an eye component cooperating therewith; arms extending from each component in divergent relationship and adapted to be pressed together at their extremities; other arms in angular relationship to these first mentioned arms and provided at their extremities with points for insertion in a collar flap; and means associated with certain of the arms, extending outwardly at an angle to the plane of the arms, and adapted to bear against the collar, for holding the hook and eye components back from the collar when a tie is inserted.

2. A collar clasp comprising components having a central portion formed to consti-

tute a hook on one component and an eye on the other; arms extending from each component and diverging outwardly therefrom; other arms carried by the first mentioned arms, in angular relation thereto and provided at their extremities with points for insertion in a collar flap; and looped portions disposed on these arms in angular

relation to the plane of the diverging arms and adapted to bear against a portion of 10 the collar flap to force the hook and eye components outwardly in spaced relation to a portion of the collar.

In testimony whereof I affix my signature.

ALFRED E. GARDNER.
